UNITED STATES PATENT OFFICE

1,998,143

NECKTIE

Samuel Newman, Philadelphia, Pa.

Application December 25, 1931, Serial No. 583,155

3 Claims. (Cl. 2—146)

This invention relates to the art of neckwear, and more particularly to improvements in the manufacture and design of neck-ties, scarfs and other such articles of manufacture wherein the design of the material of which the said articles are made requires the utmost care in securing symmetry of design and a minimum waste of material.

Among the principal objects of the present invention is to provide a method for facilitating and rendering more economical the attainment of symmetry in design of neck-ties and the like, particularly in those cases where, because of the peculiar design or pattern of the tie material, considerable waste of material is had unless the principles of the present invention are followed.

A further object of the invention is to provide a fabric which is so predeterminedly designed at the mills as to permit a greater number of ties to be produced therefrom than has been possible heretofore and prior to this invention.

A still further object of the invention is to provide a fabric of predetermined design upon which are laid out a plurality of complementary pairs of tie sections, the arrangement being such that the sections may be cut out of the fabric without the exercise of more than ordinary skill and with a minimum waste of material, each pair of sections being immediately adapted for assembly into a completed tie.

Still another and important object of the invention is to so prepare a fabric particularly adapted for the manufacture of ties and the like that the necessity for employing skilled and expensive layout men and designers in the tie manufacturing establishment is entirely eliminated, it being merely necessary at this establishment to cut the fabric along predeterminedly established lines to secure the desired sections of which the tie is made up. In other words, this invention provides a fabric, which may be in the form of a single sheet or bolt of any size, wherein appears not only the material design or configuration but also the outline defining the tie sections.

Still another object of the invention is the preparation of a fabric particularly designed for the manufacture of neckties and the like wherein symmetry of design in each tie may be secured without necessitating any waste whatsoever of the fabric.

Still other objects of the invention and advantages thereof will appear more fully herein-after.

The invention consists substantially in the com-

bination, construction, location and relative arrangement of parts, all as will appear more fully hereinafter, as shown in the accompanying drawings and as finally pointed out in the appended claims.

In the said accompanying drawings:

Figure 1 is a view showing the two sections of a tie in assembled relation prior to folding the longitudinal edges thereof into final position;

Figure 2 is a top plan view of a completed tie; 10

Figure 3 is a rear plan view of the completed tie;

Figure 4 is a plan view of a section of fabric as prepared in the mill in accordance with the principles of the present invention;

Figure 5 is a modification of Figure 4; and

Figure 6 is a further modification of Figure 4.

Referring now to the drawings and more particularly to Figures 1 to 3, it will be observed that the form of neck-tie with which this invention is concerned is generally made up of two sections 10 and 11, the section 10 having the divergent side edges 12 and 13 and the section 11 having the divergent side edges 14 and 15. As appears quite clearly in Figure 1, the sections 10 and 11 are relatively so arranged in the assembly thereof as to bring a portion of the edge 14 of the section 11 into substantial coincidence with a portion of the edge 13 of the section 10, the coinciding portions being then secured together by sewing 30 or otherwise as indicated by the broken line 16.

With the sections 10 and 11 secured together in the manner just described, the longitudinal edge portions thereof are respectively folded over the central body of the tie along the lines 17 and 18 to form the completed tie as shown in Figures 2 and 3. Usually, it is desirable to insert a canvas lining or the like between the central body portion of the tie and the folded portions thereof to give substance and form-retaining characteristics to the tie. The longitudinal edges 13—15 and 12—14 are secured together by sewing or otherwise along the line 19 (see Figure 3).

It will be observed that in the tie shown in Figures 1 to 3 the opposite ends thereof are respectively pointed or tapered and are provided with a design, indicated by the reference numerals 20 and 21 to give a finished appearance thereto. It will be seen that these end designs are symmetrical with respect to the median line of the completed tie and this is as it should be if the tie is properly designed. In the usual manufacture of ties, the manufacturer is faced with the problem of obtaining as many pairs of tie sections 10 and 11 as is possible from a single 50

piece of material with a minimum waste thereof. In the design of ties having end border designs which are geometrically symmetrical, it has been possible to obtain the same only from a fabric 5 of substantially square outline, the section 10 being obtained from one corner of this square piece of fabric and the section 11 being obtained from the diagonally opposite corner thereof. This, of course, involved a considerable waste of material because the remaining portions of the fabric 10 could not be used without sacrificing symmetry of design.

It is to avoid this very objectionable feature and to render more economical the manufacture 15 of neck-ties, scarfs and the like that the present invention is concerned with. Referring more particularly to Figure 4, it will be seen that this invention contemplates the production in the mill where the fabric is produced a fabric having 20 incorporated therein a predeterminedly established design in the form of a plurality of complementary pairs of tie sections. In Figure 4 the tie sections which correspond to the section 10 of Figure 1 are designated by the reference numeral 22, while the tie sections which correspond to the section 11 of Figure 1 are designated by the reference numerals 23. It will be observed 25 that the sections 22 each include as an integral part of the design or pattern thereof the end border design which is designated in Figure 1 by the reference numeral 21. Similarly, the end border design 20 is included as an integral part 30 of the design or patterns of the sections 23.

The fabric, as it is prepared in the mill may, of course, include any desired pattern or design and it will be understood that this design may be woven into the fabric or it may be printed thereon. Furthermore, the fabric as it is produced in the mill will, in one form of the invention, include 35 the definite lines of demarcation 24 and 25, these lines serving as guides for the tie manufacturer to cut out the sections 22 and 23. It will be, of course, understood that when the several pairs of sections 22 and 23 are cut out 40 of the fabric as received from the mill along the lines as indicated, each section 22 will be secured to its complementally formed section 23 as indicated in Figure 1.

Obviously, the fabric as produced in the mill 50 and bearing the predeterminedly configured tie sections may be in the form of a single piece of fixed dimension and from which say one dozen complete ties may be fabricated, or it may be in the form of a bolt of material from which a great 55 number of complete ties may be fabricated. Furthermore, while the outline of the several tie sections 22 and 23 for any given piece of fabric may be constant in all cases to insure 60 ties of uniform size, the pattern or configuration appearing in one pair of tie sections may be different from that in the next pair of tie sections. Similarly, the basic color of one pair of tie sections may differ from that of another pair of tie 65 sections, although each of said tie sections will be included within a single piece of the fabric.

In Figure 5, the lines of demarcation between the several tie sections appear in the form of spaces rather than as definite lines as in Figure 70 4, these spaces between the several tie sections being designated generally by the reference numeral 26.

In Figure 6 is shown an arrangement wherein a plurality of complementary pairs of tie sections 75 27 and 28 are included in a single piece of fabric,

the several complementary pairs of sections being, however, of contrasting colors. In such case, definite lines or spaces of demarcation are not necessary between each pair of sections because the contrast in colors are of themselves sufficient 5 to furnish guides for cutting them out of a fabric. The sections 27 are, however, respectively separated from their complementary sections 28 by the lines 29 which may be printed on or woven in the fabric during the course of its manufacture in the mill. 10

From the foregoing, it will be apparent that when the fabric is prepared in the manner just described in the mill and is then so furnished to the manufacturer of the neck-ties or scarfs or 15 the like, the latter is enabled to obtain from a single piece of fabric a far greater quantity of uniformly and symmetrically designed pieces than has been possible heretofore. In addition 20 to this, the manufacturer of the finished article is not required to employ skilled designers whose function it is to properly lay out the tie sections upon the piece of fabric to secure the most symmetrical design because this is automatically 25 taken care of in the fabric as supplied to the manufacturer. Another important advantage of the invention in addition to those already enumerated is that the manufacturer effects a great saving by reason of the fact he encounters no waste of material in the manufacture of the completed article. 30

It will be understood, of course, that the invention is susceptible of various changes and modifications other than those hereinbefore set forth without departing from the real spirit or 35 general principles of the invention and it is accordingly intended to claim the invention broadly, as well as specifically, as indicated by the appended claims.

What is claimed as new and useful is:—

1. A piece of material having outlined on the surface thereof during the manufacture thereof and in accordance with a predetermined uniform pattern a plurality of pairs of complementary tie sections to form two sets thereof, the first set of 40 said sections terminating in substantially triangular portions whereby to form a series of triangular spaces therebetween, the apices of said triangular spaces being spaced from either edge of the material and said spaces being respectively 45 occupied by the sections constituting the second set thereof, each of said sections being individually ornamented in accordance with a predetermined design, the ornamentation of said sections being such that when the edge of one section 50 properly adjoins that of its complementary section the design in said adjoining sections is substantially uninterrupted. 55

2. A method of manufacturing neck-ties which consists in outlining upon the surface of a piece 60 of material during the course of manufacturing said material and in accordance with a predetermined pattern a plurality of pairs of complementary tie sections, in providing that each of said pairs includes a large section of which the larger 65 end of the tie is formed and a small section of which the smaller end of the tie is formed, in individually ornamenting each of said sections so as to provide pairs of tie sections of matched 70 design, in confining the ornamentation of each section within the defining lines thereof so that the predominating ornamentation appearing in the exposed surface of the completed tie is uninterrupted by the edges of the section, in cutting out of said material so fabricated at least one of 75

said large sections and a complementally configured small section, and in finally uniting said cut out sections to produce a completed tie.

3. A piece of material having outlined on the surface thereof during the manufacture thereof and in accordance with a predetermined pattern a plurality of pairs of complemental tie sections, each of said sections being individually ornamented in the course of said manufacture to in-

sure perfect symmetry of design in the completed ties, said ornamentation being confined exclusively within the perimetric lines delineating the several sections and being further of such character that when the edge of one section properly adjoins that of its complemental section the design in said adjoining sections is substantially uninterrupted.

SAMUEL NEWMAN.
